Primary Examiner — Freda S Nunn(57) **CLAIM**

We claim the ornamental design for augmented reality glasses, as shown and described.

DESCRIPTION

FIG. 1 is a front perspective view of augmented reality glasses embodying our new design.

FIG. 2 is a rear perspective view of the augmented reality glasses.

FIG. 3 is a top view of the augmented reality glasses.

FIG. 4 is a bottom view of the augmented reality glasses.

FIG. 5 is a left side view of the augmented reality glasses.

FIG. 6 is a right side view of the augmented reality glasses.

FIG. 7 is a front end view of the augmented reality glasses; and,

FIG. 8 is a rear end view of the augmented reality glasses.

1 Claim, 4 Drawing Sheets***FIG. 1***

FIG. 2

FIG. 3

FIG. 4

FIG. 5

FIG. 6

FIG. 7

FIG. 8
